UNITED STATES PATENT OFFICE.

JOHN F. LYNN, OF CHICAGO, ILLINOIS.

METHOD OF MAKING PENCIL BODIES AND THE LIKE.

Application filed August 4, 1926. Serial No. 126,977.

This invention relates to a process of forming pencil bodies from a material which may be rendered plastic under the application of a proper heat. It may be employed with advantage in the manufacture of a pencil body having the characteristics which are set forth in my co-pending application Serial No. 126,976, filed August 4, 1926.

In the manufacture of pencil bodies from fusible materials, as heretofore practiced, it has been customary to use such materials in powder or granular form. It has also been the practice to make the pencil body in halves, usually in the form of biscuits, and then by a second operation unite these halves or biscuits to form complete bodies. The manufacture of pencil bodies by any such process is attended with certain difficulties, such as the use of the correct amount of material for each moulding operation, the elimination of a parting line when the pencil halves are united, etc. Also, the die moulds for the production of pencils according to such processes has involved considerable expense, thus adding to the difficulties in the way of their use.

According to the present invention I am enabled to proceed expeditiously with the manufacture of pencil bodies from a fusible material which is solid at the time of its handling. This material may be in the form of small strips cut to a predetermined length so as to contain the exact amount of material necessary for the moulded product. If desired, the material to be handled may be tubular in form, but in either case the requisite number of pieces supplies to the mould the correct quantity of material, it being unnecessary to resort to weighing or other procedure to determine the correct amount.

An exemplification of my invention is shown in the accompanying drawings, in the manner following:

Figure 1 is a top plan view of a frame containing die moulds wherein are formed certain products in accordance with my invention;

Fig. 2 is a vertical section through the moulds before the application of pressure thereto;

Fig. 3 is a similar view showing the moulds under compression;

Figs. 4 and 5 are transverse sections taken

respectively on lines 4-4 and 5-5 of Figs. 2 and 3;

Fig. 6, which is an enlarged detail in transverse section, shows a tubular sleeve arranged over an elliptical mandrel, as these parts appear previous to pressure from the dies;

Fig. 7 is an enlarged sectional view through the moulds, taken on line 7-7 of Fig. 3;

Fig. 8 is a longitudinal section through the product which is formed from the dies herein illustrated;

Fig. 9, which is a longitudinal section through the die moulds prior to compression, shows therein the fusible material whereof one part is tubular in form;

Fig. 10 is a transverse section therethrough on line 10-10 of Fig. 9;

Fig. 11, which is a view similar to Fig. 10, shows the dies as compressed during the moulding operation; and

Fig. 12 is a longitudinal section through a pair of moulds, designed for the production of another form of article, such, for example, as the barrel of a fountain pen.

In carrying out the present process, I employ a boxlike frame A having vertical end walls 15 and a removable side 16, which is adapted to be held in closed position by any suitable means. Within this frame is accommodated a pair of die moulds B and C adapted to be compressed between platens D, with one of which may be associated a suitable cylinder mechanism E. Between the ends of the moulds and the frame walls 15 are blocks 17 adapted to support mandrels 18 and 19. As shown, the two mandrels extend toward each other in mutual alignment, one of them being reduced to an elliptical contour for a substantial portion of its length, as at 20. A slight space intervenes, by preference, between the proximate ends of the two mandrels.

To produce a pencil body of the kind herein contemplated, I slip over each of the two mandrels 18 and 19 a circular sleeve 21, and also over the mandrel portion 20 another circular sleeve 22 of lesser diameter. Preheated strips 23 of fusible material are then laid adjacent to the opposite sides of the larger sleeves and other shorter strips 24 upon opposite sides of the smaller sleeve 22, so as to receive pressure from the dies when the same are moved toward each other

in response to pressure from the platens. Heat in a sufficient degree is then applied to reduce the fusible material to a plastic state, the heaters being preferably carried by the platens, as indicated at 30.

When the dies come together they will move from the position of Fig. 4 to that which is shown in Fig. 5. Any excess of material in the dies may escape through small openings into crevices 25 formed at the ends of the moulds. It is to be noted that the circular sleeve 22 surrounding the elliptical mandrel portion is compressed by the action of the dies so as to assume a corresponding elliptical shape. This change in cross section is clearly illustrated by reference to Figs. 6 and 7.

The moulding operation just described contemplates the use of fusible material which may conveniently be in the form of strips. These may be pre-formed to the exact size and shape which it is desired to use, thereby assuring a correct amount of material for each moulding operation. It is possible, however, to handle the fusible material in the form of a cylinder 26 which is extended over the mandrels, as shown in Fig. 9. This requires the handling of but one piece of material instead of four, as previously explained. The behavior of this material, when subjected to heat and pressure, is the same as already noted.

The product resulting from the moulding process just described appears in Fig. 8. Here is shown a body having at each end a cylindrical chamber with metallic lining therein, one of these chambers at the end being in communication with the adjacent elliptical chamber, which also is equipped with a lining of similar contour. Between this inner chamber and the one adjacent is a thin wall 27 produced by flow of the fusible material through the space intervening between the adjacent ends of the two larger mandrels. Such a pencil body has many desirable characteristics, particularly when associated with an operating member at the tip of the kind set forth in my copending application already referred to.

The present invention may advantageously be used in the manufacture of objects other than pencil bodies. For example, I have suggested in Fig. 12 a cylindrical fountain pen barrel 28 which may be formed with the aid of companion dies B and C similar in all respects to the ones already described. Projecting from one of the end blocks 17 is a single mandrel 29 which produces in the completed product a chamber adapted for the reception of ink.

I claim:

1. The method of forming a pencil body in which is a lined axial chamber at each end, which consists in extending a pair of aligned mandrels between a pair of die

molds, in fitting upon each mandrel a sleeve, in placing between the molds on opposite sides of the sleeves strips of fusible material, and in then applying pressure and heat to the dies whereby to fuse in one operation the strips of material into an integral body in which the sleeves form linings for the end chambers thereof, substantially as described. 70

2. The method of forming a pencil body in which is an axial chamber having a metallic lining of elliptical contour, which consists in extending an elliptical mandrel between a pair of die moulds, in fitting over the mandrel a circular sleeve, in placing between the molds a quantity of fusible material, and in then applying pressure and heat to the dies whereby to fuse the material into an integral body in which the sleeve is deformed into an elliptical lining for the chamber within the body, substantially as 80 described. 75

3. The method of forming a pencil body in which is a lined axial chamber at each end, which consists in extending a pair of aligned mandrels between a pair of die moulds the adjacent ends of which are slightly separated, in fitting over each mandrel a sleeve, in placing between the moulds a quantity of fusible material, and in then applying pressure and heat to the dies 90 whereby to fuse the material in one operation into an integral body having a cross wall through the space between the mandrels, the sleeves forming linings in the end chambers of the body, substantially as 95 described. 100

4. The method of forming a pencil body having at one end an axial chamber which is circular in its outer portion and elliptical throughout its inner portion, which consists in extending between a pair of die moulds a mandrel having a circular cross section throughout one portion of its length and an elliptical cross section throughout the remaining portion of its length, in applying circular sleeves to the two portions of the mandrel, in placing between the moulds a quantity of fusible material, and in then applying pressure and heat to the dies whereby to fuse the material into an integral body in which the sleeves form linings for the axial chamber therein, the inner sleeve being deformed to an elliptical contour corresponding substantially to that of the mandrel on which it is fitted, substantially as described. 110 115

5. The method of forming a pencil body having an axial chamber in each end, which consists in placing within an open frame a pair of die moulds adapted to receive pressure from an outside source, in fitting between the ends of the moulds and proximate walls of the frame a pair of blocks each carrying a mandrel which extends toward the other between the moulds, in fitting over 125 130

each mandrel a metallic sleeve, in placing between the moulds and on opposite sides of the sleeve a quantity of fusible material, in applying pressure and heat to the dies whereby to fuse the material in one operation into an integral body in which the sleeves form linings for the end chambers thereof, and finally in withdrawing the moulds from the body and the mandrels 10 from the sleeves, substantially as described.

6. The method of forming a hollow pencil body, which consists in placing between a pair of die moulds having a mandrel extended centrally between them a quantity 15 of fusible material in solid form which is disposed on opposite sides of the mandrel, and in then applying pressure and heat to

the dies whereby to fuse the material in one operation into an integral body, substantially as described. 20

7. The method of forming a pencil body having a chamber proceeding inwardly from an end thereof, which consists in extending between a pair of die moulds a mandrel conforming in size and form to said chamber, in placing between the moulds and on opposite sides of the mandrel a strip of solid fusible material, and in then applying pressure and heat to the dies whereby to fuse the material in one operation into an 25 integral body from which the mandrel is removable, substantially as described. 30

JOHN P. LYNN.
